UNITED STATES PATENT OFFICE.

GEORGE L. PIERCE, OF BROOKLYN, NEW YORK, ASSIGNOR TO A. G. SPALDING & BROS.,
OF NEW YORK, N. Y., A CORPORATION OF NEW JERSEY.

GOLF BAG.

Application filed March 18, 1927. Serial No. 176,321.

The present invention relates in general to golf bags, particularly the light bags of the so-called "Sunday" type, and it is proposed to provide an improved bag wherein the ball 5 pocket is attached to the strap of the bag and the inconvenience and undesirability of attaching it to the side of the bag are overcome. Obviously, the invention may be applied to many forms of bags and similar articles although it will be described in connection with golf bags.

There is no specific form of bag upon which this invention is designed to be used and it is found to be highly practical on all forms. 15 Although adapted for use with any bag, it is particularly useful and economical on a bag of the type comprising a continuously knitted cylindrical stocking with a suitable base and no stays. In manufacturing bags, 20 considerable difficulty is encountered in attaching the ball pocket to the side wall of the bag, and the present invention proposes to attach it directly to the shoulder strap before the latter is secured to the bag, whereby 25 the bag can be completed without the necessity of attaching the ball pocket thereto. It is quite obvious that the pocket could be removably attached to the strap, as by snaps, rings or other suitable means, in which case 30 the bag and strap could be first made and the pocket attached later.

Reference will now be had to the accompanying drawings forming a part hereof, wherein:

35 Figure 1 is a view, in perspective, of the bag of the proposed form showing the ball pocket attached to the strap.

Figure 2 is a section taken on line 2—2 of Figure 1, showing the bellows type of ball 40 pocket.

Figure 3 is a section through the pocket, showing its configuration while containing a ball.

Figure 4 is a section on line 4—4 of Figure 1.

45 In the drawings, *a* represents a bag formed of a continuously knitted canvas or the like which requires no seam to complete the cylindrical shape of the bag. This is illustrated by Figure 4 wherein a section of the bag is 50 shown. By knitting the bag in this manner, they may be manufactured with great facility since a continuous stocking is available, suitable lengths of which are cut off to form individual bags. It is extremely difficult to sew the ball pocket to the bag, since 55 it is made in a cylindrical form. Lengths of the stocking are finished by applying the bottom *b* and top rim *c*.

60 A pocket *d*, formed as indicated in Figure 2 is sewed to the lower end of the strap *e* as indicated at *f* in Figure 2. This pocket may be of any form and is provided with a flap *g* and securing means *h* as shown in Figure 1. The strap is sewed to the bag in the usual 65 manner as at *i* and the ball pocket interferes, in no way, with the function of the strap. Figure 3 illustrates a ball *j* carried in the pocket.

70 It is obvious that the specific design of the bag may be altered and the relation of parts changed without departing from the scope of the invention as defined in the appended claim.

75 What I claim is:

In a golf bag formed of a seamless one-piece bag portion and a strap secured thereto, a strip of material attached to the strap at its side and forming with the strap a bellowsed ball pocket.

80 This specification signed this 15th day of March A. D. 1927.

GEORGE L. PIERCE.
